Primary Examiner — Austin Murphy(74) *Attorney, Agent, or Firm* — Birch, Stewart, Kolasch & Birch, LLP(57) **CLAIM**

The ornamental design for a bluetooth dongle, as shown and described.

DESCRIPTION

FIG. 1 is a perspective view of the bluetooth dongle showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is a reference view thereof showing the state that the earphone is attached to the subject design; and,

FIG. 8 is a reference view thereof showing the state that the subject design is attached to the case.

The broken lines depict portions of the bluetooth dongle that form no part of the claimed design.
